CLAIM

The ornamental design for a string dispenser, as shown and described.

DESCRIPTION

FIG. 1 is a perspective view taken from the left front of the string dispenser according to my invention;

FIG. 2 is a front elevational view of the string dispenser of FIG. 1;

FIG. 3 is a back elevational view of the string dispenser of FIG. 1;

FIG. 4 is a side elevational view of the right side of the string dispenser of FIG. 1 with the left side being a mirror image;

FIG. 5 is a top plan view of the string dispenser of FIG. 1; and,

FIG. 6 is a bottom plan view of the string dispenser of FIG. 1.
